UNITED STATES PATENT OFFICE.

JOHN E. FITZGERALD, OF BOSTON, MASSACHUSETTS.

TAG-FASTENER.

1,237,769.

Specification of Letters Patent. Patented Aug. 21, 1917.

Application filed July 14, 1916. Serial No. 109,343.

To all whom it may concern:

Be it known that I, JOHN E. FITZGERALD, a citizen of the United States, residing at Boston, in the county of Suffolk and State 5 of Massachusetts, have invented a new and useful Tag-Fastener, of which the following is a specification.

The present invention appertains to tag fasteners, and is particularly an improvement over the tag fastener disclosed in my 10 Patent No. 1,158,912, granted November 2, 1915.

It is the object of the invention to provide extremely simple and inexpensive yet 15 thoroughly efficient and practical fastening means easily applicable to a tag and bendable into engagement with a binding cord wrapped around the bundle or package to which the tag is applied, whereby the tag 20 will be effectively held in place, without danger of its being accidentally displaced or lost during transit.

With the foregoing and other objects in view which will appear as the description 25 proceeds, the invention resides in the combination and arrangement of parts and in the details of construction hereinafter described and claimed, it being understood that changes in the precise embodiment of the invention herein disclosed can be made within 30 the scope of what is claimed without departing from the spirit of the invention.

The invention is illustrated in the accompanying drawing, wherein:—

35 Figure 1 is a perspective view illustrating a tag applied to a package or bundle with one of the fasteners unbent and the other bent into engagement with the binding cord.

Fig. 2 is a fragmental back view of the tag 40 illustrating one of the fasteners.

Fig. 3 is a sectional view on the line 3—3 of Fig. 2.

Figs. 4 and 5 are back views of modified forms of fasteners.

45 Fig. 6 is a plan view of another variation.

Fig. 7 is a back view of a double fastener similar in its general construction with the fastener shown in said patent.

Fig. 8 is a perspective view of another 50 form of the invention.

As illustrated in Fig. 1, a pair of the fasteners is applied to the tag 1 adjacent the opposite ends thereof, but it is to be understood that in some cases a single fastener may suffice, whereas in others more than two fasteners can be used if desired or necessary. The

tag 1 can be of paper, card board, or any other suitable material, and can be of any suitable size or shape, since the present fasteners are applicable to various tags.

60

Each fastener consists solely of an elongated plate or short strip 2 of suitable sheet metal or other material which can be readily bent by hand, but which will not be liable

to unbend accidentally. The central or body 65 portion of the elongated plate 2 is provided

with a pair of opposite elongated longitudinal lips or tabs 3 cut therefrom and providing an elongated or rectangular longi-

tudinal opening therebetween centrally of 70 the plate. Said lips 3 are disposed at oppo-

site sides of said opening adjacent to and parallel with the side edges of the plate.

The lips or tabs 3 are engageable through 75 the tag 1, the two fasteners being prefer-

ably disposed transversely upon the front or other surface of the tag 1, adjacent the ends thereof. The lips 3 can be extended

through openings 4 with which the tag is 80 provided, or said tag can be provided with

slits for the passage of the lips, which ever 85 is desired, and the lips after being engaged through the tag are bent back or reflexed

away from one another toward the rear side of the fastener to overlap the rear face of 90 the tag, and thus clamp the fastener firmly

in place. The end portions of the plate 2 provide bendable ears 5 projecting in oppo-

site directions and normally lying flat upon 95 the tag. The fold lines of the ears 5 coincide with the ends of the opening of the plate,

it being noted that the weakest portions of 100 the plate lie on the transverse lines of the ends of said opening. The body portion of

the plate between the ends of the opening is 105 reinforced due to the bending back of the

lips 3, said lips providing doubled portions which are relatively stiff, so that no scores

need be made in the metal to facilitate the 110 bending of the ears. When the ears are bent back toward the front side of the plate,

the ears will naturally bend on the fold lines which coincide with the ends of the opening of the plate. Therefore, it will be evident

that the plate 2 can be readily stamped from 115 sheet metal, and applied to the tags by

simply clenching the plate to the tags by

means of the lips 3 which are engaged

through and behind the tag.

The tag 1 can be readily placed against 120 the package or bundle 6 and held there-

against after the binding cord 7 is passed

around the package and tied. The tag is so arranged that the binding cord extends longitudinally over the tag and transversely over the fasteners. To fasten the tag, it is 5 simply necessary to bend back the ears 5 toward the binding cord so that the ears overlap one another and embrace the cord, to thus hold the fastener in place during the handling and transportation of the package 10 or bundle.

In the modification shown in Fig. 4, the tabs 3^a are arranged at the ends of the central opening of the plate 2^a and are adapted to engage through the tag and to be bent 15 back away from one another toward the ears 5^a. This will also serve to confine the bending of the plate on the transverse fold lines coinciding with the ends of the opening.

20 The tabs or lips 3^b of the plate 2^b shown in Fig. 5 are arranged the same as the lips or tabs 3, but are shorter in length than the opening, but can be of greater dimensions from their basal to their free edges. The 25 tabs 3^b are located adjacent the opposite ends of the opening and are diagonally opposite one another.

The fastener illustrated in Fig. 6 does not have the tabs or clenching means struck 30 from the body portion thereof, but the lips or tabs 3^c project from the side edges of the central or body portion of the plate 2^c, while the bendable ears 5^c are arranged at right angles with the tabs 3^c. This fastener 35 is of cruciform shape, and the tabs 3^c can be passed through slits in the tag so as to project in opposite directions and overlap the rear face of the tag. These tabs 3^c also serve to cause the ears 5^c to bend on trans- 40 verse lines which practically coincide with the ends of the tabs 3^c.

A double fastener is shown in Fig. 7, the two transverse plates or fasteners 2 being connected by a longitudinal strip 8 hav-

ing its terminals integral with the central or body portions of the plates 2. The plates 2 are the same as those illustrated in Figs. 1, 2 and 3, or the plates shown in Figs. 4 and 5 can be used.

As shown in Fig. 8, the fastener has an 50 annular series of spurs 3^d struck therefrom to be clenched through the tag, and there being a circular eyelet opening instead of the rectangular one.

Having thus described the invention, what 55 is claimed as new is:

1. A tag fastener adapted to rest flatly against one side of a tag and having oppositely projecting ears adapted to be bent back to embrace a binding cord, and means 60 struck from between said ears to engage through the tag.

2. A tag fastener embodying a plate adapted to rest flatly against one side of a tag and whose end portions provide ears 65 which are adapted to be bent back into overlapping relation to embrace a binding cord, the central portion of the plate having a plurality of tabs struck therefrom between said ears to engage through and overlap 70 the opposite side of the tag.

3. A tag fastener embodying an elongated plate adapted to rest flatly against one side of a tag, the central portion of the plate being provided with tabs struck therefrom between said ears to provide an opening, said tabs being engageable through the tag to overlap the opposite side thereof, and the end portions of the plate providing ears adapted to be bent back into overlapping re- 80 lation to embrace a binding cord.

In testimony that I claim the foregoing as my own, I have hereto affixed my signature in the presence of two witnesses.

JOHN E. FITZGERALD
